UNITED STATES PATENT OFFICE.

BURR BAKER, OF MINNEAPOLIS, MINNESOTA.

FIGURE TOY.

Application filed June 19, 1924. Serial No. 720,992.

To all whom it may concern:

Be it known that I, BURR BAKER, a citizen of the United States, residing at Minneapolis, in the county of Hennepin and State of Minnesota, have invented certain new and useful Improvements in Figure Toys; and I do hereby declare the following to be a full, clear, and exact description of the invention, such as will enable others skilled in the art to which it appertains to make and use the same.

My invention provides an amusing toy, which comprises an oscillatory toy punching bag and a toy figure arranged to punch the said toy bag. The toy figure is preferably made to represent a boxing kangaroo and is provided with a long and heavy projecting tail portion serving as a weight to normally hold the toy figure retracted from the punching bag.

In the accompanying drawings, which illustrate the invention, like characters indicate like parts throughout the several views.

Referring to the drawings:

Fig. 1 is a side elevation showing the improved toy;

Fig. 2 is a front elevation of the moving figure, some parts being sectioned on the line 2—2 of Figure 1; and

Fig. 3 is a section on the line 3—3 of Fig. 1.

The toy punching bag 4 may be of any suitable material, but preferably of a quite heavy material, such as wood, and at its upper end, it is provided with a screw eye 5 that is loosely connected to an eye 6 formed in the top portion of a yoke-like pedestal 7, the lower ends of the legs of which, as shown, are rigidly connected to a base block 8 by clamping devices 9 of the binding post type.

The numeral 10 indicates the body of a toy figure, which, as stated, is preferably made to represent a boxing kangaroo and is provided with a long heavy tail portion 11 that serves as a counterweight. The lower portion of the Figure 10 is pivotally connected by a bolt 12 to a pronged bracket 13 rigidly secured to the base block 8. The foot-forming portion of the Figure 10 projects forwardly and, as shown, between the legs of the pedestal 7. Said Figure 10 is provided

with pivoted arms 14 connected thereto by a bolt or rivet 15. The ends of the arms 14 are enlarged in imitation of boxing gloves. 55 The bolt or rivet 15 will be tightened so that the arms 14 will not freely swing or accidentally move, but may be pivotally adjusted so that they will properly strike against the toy punching bag 4. An operating cord 16 is attached to the intermediate front portion of the toy body 10 by an eye bolt 17. When the cord 16 is quickly jerked, the toy Figure 10 will be oscillated on its pivot 12, thereby causing the large ends of the arms 14 to strike the punching bag 4 much in imitation of an actual bag-punching action. In the device illustrated, the toy figure being a kangaroo, its arms are not set to freely swing, but said arms may be loosened, if desired, and set free for a swinging action. A very amusing action may be produced by imparting a quick succession of jerks to the operating cord.

The toy figure may be made from wood or any other suitable material. The base block 8 may be fastened to any suitable support, such as a board, the upper surface of which is indicated by the line marked 18.

It will be noted that the head, or rather, 80 the nose portion, of the oscillatory Figure 10 is so arranged that it will strike the punch bag if the arms 14 should be out of place, and this is especially important when the arms are left free to swing, so that they 85 would not always strike the punch bag, even if the toy figure should be projected toward the bag. The forwardly projecting foot portion of the oscillatory figure will engage the base block to limit the extreme forward 90 movement of the figure toward the punch bag.

What I claim is:

1. A toy comprising a base, a yoke-like pedestal secured to and rising from said base, a toy punch bag loosely hung from the upper transverse portion of said pedestal, a toy figure pivoted to said base and having arms arranged to engage said punch bag, said toy figure having a forwardly projecting foot portion limiting the movement of the said figure toward the punch bag, and having a heavy outwardly projecting tail portion serving as a weight normally hold-

ing said figure retracted from the punch bag, and an operating cord attached to said toy figure.

2. A toy comprising a base, a yoke-like pedestal secured to and rising from said base, a toy punch bag loosely hung from the upper transverse portion of said pedestal, a toy figure pivoted to said base and having

arms arranged to engage said punch bag, and an operating cord attached to said figure 10 for imparting a quick succession of oscillations thereto, the head of said figure being located for movement on a line toward and intersecting the punch bag.

In testimony whereof I affix my signature.
Burr Baker.
